UNITED STATES PATENT OFFICE.

EUGENE W. YEARSLEY, OF BROOKLYN, NEW YORK, ASSIGNOR TO THE S. S. WHITE DENTAL MANUFACTURING COMPANY, A CORPORATION OF PENNSYLVANIA.

AIR-COMPRESSOR.

1,370,254.

Specification of Letters Patent.

Patented Mar. 1, 1921.

Application filed April 3, 1918. Serial No. 226,389.

To all whom it may concern:

Be it known that I, EUGENE W. YEARSLEY, a citizen of the United States, and a resident of Brooklyn, in the county of Kings,

5 State of New York, United States of America, have invented certain new and useful Improvements in Air-Compressors, of which the following is a specification, reference being had to the accompanying drawings.

10 My invention relates to that class of air compressors that are particularly adapted to the use of dentists, or other such professional operators, and to uses requiring a light compact and noiseless compressor or

15 vacuum producing pump.

The principal objects of my invention are to provide an air compressor that is substantially noiseless in its operation, positive in its action, simple in its construction,

20 and easily accessible for repair.

Another object of my invention is to provide an air compressor so constructed and arranged that the piston relieves the valve of the maximum cylinder pressure, and thereby not only reduces wear, but permits of a lightened construction and consequent quick response of the valve.

Other objects of my invention are to provide an air compressor with valves so con-

25 structed and arranged as to be inexpensive, light, flexible and readily replaced, to provide valves that are delicate but positive in action and that will tend to maintain their seats free from dirt or grit, and to pro-

30 vide said valves with seats that are readily removable and interchangeable.

Further objects of my invention are to provide an air compressor that may be as readily employed as a vacuum producer, and that is so constructed and arranged as to require a minimum clearance, and permit the piston to travel to the end of the cylinder.

Specifically stated, the form of my invention as hereinafter described, comprehends an air compressor, provided with a compression cylinder having its exhaust port in its head and its suction port in its side intermediate of the stroke of the piston, and having replaceable valve seats comprising annular beads in relief, upon which valves formed of flexible flat metal plates are floatingly seated, being lightly engaged therewith by dished star-shaped springs, and

limited in their movement by adjusting 55 screws independent thereof.

My invention also includes all of the various novel features of construction and arrangement as hereinafter more definitely specified.

In the accompanying drawings Figure 1, is a vertical transverse sectional view taken centrally through one of the compressor cylinders; Fig. 2, is a fragmentary sectional view of said cylinder, its exhaust valve, and 60 yoke, said yoke being shown partly in elevation for convenience of illustration; Fig. 3, is a fragmentary sectional view taken transversely of the axis of the cylinder, centrally through the suction valve; Fig. 4, is a perspective view of the valve seat showing the 65 annular bead upon which the flexible plate rests; Fig. 5, is a perspective view of the valve disk or plate; and Fig. 6, is a perspective view of the star-shaped spring 70 plate which tends to maintain the valve upon its seat.

In said figures, the compressor base 1, is supported upon the reservoir 2, and carries the compressor, comprising the crank casing 80 3, cylinder 5, head 6, piston 7, pitman 9, crank-pin 10, crank 11, balance-wheel shaft 12 and balance wheel 13.

The compressor may preferably have a pair of cylinders each having an inlet or 85 suction port 15 in the side wall a substantial distance from the exhaust end, and an exhaust port 16 in the cylinder head 6, the suction ports being provided with removable valve seat bodies 17 having the annular valve seat rings or beads 18, and retained by the yoke 19 which is detachably engaged by the tap-bolt 20, and the exhaust port being provided with similarly removable valve seat bodies 21, having the annular valve seat rings or beads 22, and retained by the yoke 23, which is detachably engaged by the tap-bolt 25.

The yoke 19 is provided with the threaded nipple 26, which may be suitably connected with any suitable source of air supply, as for instance, an air washer or strainer, and connects with the air duct 27, leading through said yoke 19, in communication with the chambers 29 and ports 30 in 100 105 the valve seat bodies 17.

The yoke 23 is provided with the threaded nipple 31, arranged to be connected with

any suitable delivery union 32, by the union nut 33, and is provided with the air duct 35, leading from the valve chamber 36, through said nipple.

- 5 The inlet port 15 is controlled by the valve comprising a thin flexible sheet metal plate 37, shown in perspective in Fig. 5, fitted in the circular valve chamber 38, which is formed by the annular lip 39 projecting from the side of the cylinder, and said valve is yieldingly held against its seat 18 by the star-shaped spring 40, shown in perspective in Fig. 6. Similarly the exhaust port 16 is controlled by its valve 37 fitted in 10 the circular valve chamber 36, by the star-shaped spring 40.

The valve 37 may have its opening movement adjustably limited by the adjustment of the adjusting screw 41, which is disposed 20 in the yoke 23 in axial alinement with the valve chamber 36, and it is obvious that the movement of the valve 37 controlling the inlet port 15 may be similarly limited if desired.

- 25 The valve seat body 17, is provided in its oppositely directed plane faces with the annular grooves 42 and 43 respectively, the groove 42 being arranged to receive the lip 39 and the groove 43 is arranged to receive 30 the annular lip 45 on the yoke 19, fitted therein and as shown in Fig. 1, the grooves 42 and 43 may be provided with lead washers 46 and 47 respectively, or other suitable leak proof gaskets.

- 35 The valve seat body 21, is conveniently provided with the annular projection 49, fitted in the annular groove 50 in the cylinder head 6 in sealed relation by the gasket or washer 51, and said valve seat body 21 is 40 also provided with the peripheral flange 52 fitted into the annular groove 53 in the yoke 23 in sealed relation by the gasket or washer 55.

The valve plate 37 which is best shown in 45 perspective in Fig. 5, is preferably in the form of a disk of a diameter substantially equal to the diameter of the valve chambers 36 and 38 having four equal and oppositely disposed sectors cut therefrom for the passage of air between the chordal edges thereof and the cylindrical walls of said chambers.

It may be here noted that by disposing 55 the inlet ports in the side of the cylinder, spaced from the exhaust end, the valves are not subjected to the severe pressure incident to the final stroke of the piston, for the reason that said piston serves to close these ports at about two-third of its compression 60 stroke, this not only relieves the valves, and permits them to be of light construction, but permits a minimum clearance of the piston, and also renders the compressor capable of being employed as a vacuum pump 65 if desired.

Thus it will be seen that the air at the beginning of the upward stroke of the piston is practically atmospheric pressure and that the increment of pressure is slow during the first half of the stroke, and more rapid as 70 it approaches the maximum compression, so that up to the time when the piston passes the inlet port, the pressure has risen to a comparatively small percentage of the maximum pressure at the termination of the 75 stroke. Upon the return stroke the vacuum produced by the piston increases only during about one-third of the stroke, and is somewhat reduced by the air trapped in the clearance space, the remaining two-thirds of 80 the stroke of the piston giving ample time for inspiration of the atmospheric air to completely fill the cylinder, thereby, suffering no loss of energy, as in cylinders, wherein the intake ports are located at the 85 initial end of the compression stroke, and wherein the air is taken in in an extremely short space of time.

It will be obvious that by the arrangement of the ports thus contemplated, the 90 compressor may be as readily employed as a suction or vacuum pump if desired, which is especially advantageous for dental purposes.

My invention is advantageous, in that the valves employed comprise flexible disks that 95 require no machining and may be inserted without adjustment, and as they are free to float, have nothing to interfere with their flexibility, furthermore, this valve cooperates with a seat in the form of an annular 100 bead, from which any grit or dirt that may accidentally lodge thereon will be quickly dislodged by the floating movement of the valve disk.

My invention is further advantageous in 105 that the valve seat is readily removable and replaceable, and being circular in form can be inexpensively produced on a screw machine, and be held in place by the yoke through the medium of the tap-bolt, which 110 serves to secure said yoke and valve seat bodies to the cylinder body.

I do not desire to limit my invention to the precise details of construction and arrangement as herein set forth, as it is obvious that various modifications may be made therein without departing from the essential features of my invention as defined in the appended claims.

Having thus described my invention, I 120 claim:—

1. An air compressor having a compression cylinder provided with an air inlet port in the side thereof and an exhaust port in its head, a piston arranged to reciprocate in 125 said cylinder and to close said inlet port as it approaches the end of its compression stroke, valves for said exhaust and inlet ports comprising flexible sheet material and a spring bearing against the center of said 130

- valve, tending to force it into closed position.
2. An air compressor having a compression cylinder provided with a valved air inlet port in the side thereof and a valved exhaust port in its end, a piston arranged to reciprocate in said cylinder and to close said inlet port during the last half of its compression stroke, the valve of said air inlet being actuated by the compression in the cylinder.
3. An air compressor having a compression cylinder provided with an inlet port and an exhaust port and a reciprocatory piston operative to close said inlet port as it approximates the termination of its compression stroke, and automatically actuated valves for said inlet and exhaust ports.
4. An air compressor having a compression cylinder provided with an inlet port and an exhaust port, and a reciprocatory piston operative to close said inlet port as it approximates the termination of its compression stroke, valve seats local to said ports and valves comprising flat sheet metal disks having oppositely disposed parallel sides coöperative with said seats to control said ports.
5. An air compressor having a compression cylinder provided with an inlet port and an exhaust port, and a reciprocatory piston operative to close said inlet port, as it approximates the termination of its compression stroke, valve seats local to said ports and fluid actuated valves, comprising flat flexible sheet metal disks coöperative with said seats to control said ports.
6. An air compressor having a compression cylinder provided with inlet and exhaust ports, removable valve seat bodies comprising beads in relief forming valve-seats, and valves having alternate flat and curved sides comprising sheet material floatingly engaged with said seats.
7. An air compressor having a compression cylinder provided with ports, removable valve seat bodies forming valve chambers and comprising annular beads in relief affording valve seats, and valves comprising thin sheet material, loosely fitted in said
- chambers, and substantially flat springs disposed in said chambers tending to hold said valves floatingly engaged with their respective seats.
8. An air compressor having compression cylinders provided with ports, removable valve seat bodies forming valve chambers for the respective cylinders and comprising annular beads in relief affording valve seats, and valves comprising thin sheet material, loosely fitted in said chambers, and springs disposed in said chambers tending to hold said valves floatingly engaged with their respective seats, and a yoke serving as a conduit engaged with the cylinder body arranged to retain said valve seat bodies.
9. An air compressor having compression cylinders provided with ports, removable valve seat bodies forming valve chambers for the respective cylinders and comprising annular beads in relief affording valve seats, and valves comprising thin sheet material, loosely fitted in said chambers, and springs disposed in said chambers tending to hold said valves floatingly engaged with their respective seats, and a yoke serving as a conduit having a plurality of valve chambers arranged to register with the respective valve seat bodies, and having an air duct connecting said chambers, and means arranged to secure said yoke to the cylinder body and thereby retain said valve seat bodies.
10. An air compressor having a compression cylinder provided with ports having valve seats, comprising an annular bead in relief, valves comprising a disk of sheet material floatingly engaged with said seats, sheet metal springs tending to press said valves into engagement with their respective seats, and means adjustable to vary the reciprocatory movement of said valves toward and from their respective seats.

In witness whereof, I have hereunto set my hand this 23 day of March, A. D. 1918.
